HOSPITAL BEDSTEAD

Hassanally Khimji Khakiani, Bombay,
British IndiaApplication June 11, 1943, Serial No. 490,501
In British India June 11, 1942

15 Claims. (Cl. 5—69)

1

This invention relates to improvements in hospital-type bedsteads of the kind having a mattress-supporting frame-work and a mattress of articulated sections which in their normal unoperated or flat in-line positions are extended horizontally on said frame-work, but which are adapted to assume various inclinations relatively to one another about their articulations in order to give certain of the standard positions which are required for day-to-day use in surgical, medical and gynaecological cases.

By the term "mattress" is meant in the present specification that surface of the bedstead which is adapted to support the bedding of the occupant, such mattress generally being a metallic frame-work with the supporting surface thereof provided by crossed or interlacing metal strips, wires, slats or the like, although the material from which the same may be made may vary.

Hospital-type bedsteads of the kind referred to are already known by means of which certain ones only of the standard positions required may be obtained and in particular the two bedsteads known as the Fowler and the cardiac bedsteads have already been proposed. Both these bedsteads, however, are based on the constructional feature that the leg-rest (or seating) section of the mattress is wholly or partly directly and permanently connected to the horizontal frame-work of the bedstead and it is not possible to vary bodily the position of the leg-rest section with respect to the said frame-work, i.e. it cannot be lifted wholly and bodily above the same frame-work. In the Fowler bedstead, also, there is a knee-rest section extending above and supported on the leg-rest section and comprising two articulated flaps, the end of that knee-rest flap which is nearest the headend of the bedstead being also permanently and directly connected to the frame-work. It is the aforesaid lack of freedom of movement of the mattress as a whole which renders it impossible, both in the Fowler bedstead and the cardiac bedstead, to obtain any more than the three well-known Fowler and cardiac positions.

The present invention has for its main object to provide an improved hospital-type bedstead in which there may be obtained a larger number of standard positions than it has been possible heretofore to obtain in any other single bedstead without the use of separate mechanical or non-mechanical devices.

It has for another object to provide an improved hospital-type bedstead in which there may be obtained, without the aid of any separate me-

2

chanical or non-mechanical devices, not only a number of the aforescribed standard positions, but also a number of new positions useful in the treatment of patients.

It has for another object to provide an improved hospital-type bedstead in which there may be obtained at the same time practically all the standard positions required for day-to-day use in medical, surgical and obstetrical cases, and for convalescent patients.

It has for yet another object to provide an improved hospital-type bedstead wherein there may be obtained in all eleven positions, excluding the normal horizontal position of the sections of the mattress, out of which eight are standard positions which have never heretofore been obtainable in one and the same bedstead, and three new positions useful for convalescent patients.

It has for a further and particular object to provide an improved hospital-type bedstead in which the eleven positions aimed at in the immediately preceding paragraph are the three standard Fowler positions previously referred to, the cardiac (back-rest) position No. 1, which is the same as the Fowler position No. 1, the cardiac chair-like position No. 2, the hyperextension position, the Trendelenburg position, the reversed Trendelenburg positions Nos. 1 and 2, and three new positions, namely the convalescent positions Nos. 1, 2 and 3.

It has for a still further object to achieve the greater number of positions in one and the same bedstead aimed at in the various preceding paragraphs, by a construction of the bedstead which enables a greater freedom of movement of the entire mattress than is permitted in the Fowler, cardiac and other hospital-type bedsteads previously known.

It has for yet a further object to provide an improved construction of hospital-type bedstead which enables the greater number of positions aimed at in the preceding paragraphs to be obtained without any unduly complicated construction and mode of operation of the bedstead and employing suitable means such as simple hand-operated screw means for effecting all movements and articulations of the several sections of the mattress relatively to one another and to the bedstead frame-work.

The various novel features both as to construction and novel principles of movement and operation of the various sections of the bedstead mattress which enable the afore-described objects of the invention to be attained, and the various improved combinations of constructional

parts which separately, and in combination, form a part of the invention, will be more particularly described and ascertained in and from the following description of a preferred embodiment of the invention which is given with reference to the accompanying drawings, in which:

Fig. 1 is a diagrammatic perspective view of the constructional mechanism of the bedstead, partly broken away, with the various sections of the articulated mattress in their normal flat or un-operated positions.

Fig. 2 is a perspective view of the constructional mechanism of the bedstead with the several sections of the articulated mattress in one of their operated positions.

Fig. 3 is a perspective view from above the headend of the bedstead of the constructional mechanism of the latter in another one of the operated positions of the sections of the articulated mattress, showing certain parts of the said mechanism which either are not shown clearly in Figs. 1 and 2 or have been omitted from the latter for the sake of clarity, and

Figs. 4 to 15 show each of the 12 different positions, including the normal unoperated or flat condition of the bedstead, which may be obtained by means of the construction according to the invention.

In the following description with reference to the drawings, where the terms "headend" and "footend" of the bedstead are used, such terms are not to be understood as including any constructional features or limitations on the nature of the bedstead framework. They are merely intended to denote the ends of the bedstead which are nearest to the back-rest section and to the footend or knee-rest section of the mattress respectively. In the same way, where the term "forward" is used, this is merely intended to denote a direction of movement taken from the point of view of the operator from his position at the operating means of the bedstead looking towards the mattress and which, in the embodiment hereinafter to be described, is at the footend of the bedstead, the said "forward" direction therefore being from the footend towards the headend of the bedstead.

With reference to the aforesaid drawings, the construction of bedstead illustrated comprises the usual tubular metal headend 1 and footend 2 which support the usual rectangular mattress-supporting frame-work T. The mattress itself is made up of three articulated sections, namely a back-rest section D articulated at one end on a hinge-rod M to one end of a leg-rest section E. Extending above and supported on the said leg-rest section E is a knee-rest section comprising two flaps F articulated together about a hinge-rod F₁ and at their other ends to the leg-rest section E.

The said articulated mattress composed of the back-rest section D, the leg-rest section E and the knee-rest section F is therefore without any direct and permanent pivotal or like connection to the said frame-work and, as will be described more particularly hereinafter, this is an important constructional feature of the mattress which enables the greater number of standard positions of the articulated sections thereof as are aimed at by the invention to be obtained.

At the footend 2 of the bedstead frame-work is secured to the underneath of the frame-work T a bracket member consisting of the component members 3 and 4, the component 4 being secured by means of suspension members 5 to the side

members of the frame-work T. Between and supported by the said components 3 and 4 of the bracket extend three operating screws A, B and C, spaced vertically one above the other, and which are provided for working, through respective force transmitting means in the form of link systems hereinafter to be described, the back-rest section D, leg-rest section E and knee-rest section F of the mattress respectively.

As is clearly shown in the drawings, the lowermost operating screw A has mounted on the same an outwardly bottle-shaped metal moulded but internally tubular and threaded traversing block or sleeve A₁ to which are pivotally connected on either side forwardly extending operating link-rods A₂. The said link-rods A₂ are connected to the respective ends of a cross-bar D₃ to which are also pivotally connected, at each side, two link-rods D₁ which are pivotally connected at their other ends respectively to the headend and footend of the said back-rest section D as shown in the drawings. The arrangement provides a force transmission system between the screw A and the section D which is such that if the screw A be turned, the threaded sleeve A₁ is caused to travel forward on the said screw towards the headend of the bedstead and, upon doing so, moves the operating link-rods A₂ in the forward direction. These link-rods A₂ move the back-rest section supporting link-rods D₁ upwards in a circular movement and the back-rest section D is caused to rotate upwardly from its normal horizontal position about the hinge-joint M which articulates the same to the leg-rest section E. The different operated positions which may be secured by operating the back-rest section from normal in such manner are shown in Figs. 4, 5, 8, 10, 12 and 14 and will be more fully and particularly described hereinafter.

The middle operating screw B has also mounted on the same a bottle-shaped metal moulded internally tubular threaded sleeve B₁ to which are pivotally connected on either side forwardly extending operating link-rods B₂.

The operating link-rods B₂ of the screw B are fixed at their forward ends to the respective ends of a cross-bar B₆. At its outer ends, the said cross-bar B₆ has mounted thereon runner wheels B₃ which are adapted to bear and run in respective upwardly inclined wheel-guides or rails B₅ secured in a suspended manner to the respective side members of the frame-work T, the direction of inclination of the said wheel-rails or guides B₅ rising towards the headend 1 of the bedstead as shown. At each side, and intermediate the point of connection of the respective operating link-rods B₂ and runner wheel B₃, the said cross-bar B₆ has pivotally mounted thereon connecting link-rods B₄, the upper end of each of which is pivotally connected to a corresponding downwardly depending lug E₁ on the headend of the leg-rest section E, a short distance from the articulation of the said leg-rest section with the back-rest section D about the hinge-rod M.

The topmost operating screw C has also mounted on the same a bottle-shaped metal moulded internally tubular threaded traversing block or sleeve C₁ to which are pivotally connected on either side forwardly extending operating link-rods C₂. These link-rods are pivotally fixed to a cross-bar C₅ which in turn is loosely rivetted to the bent-over side members 6 of that flap F of the knee-rest section which is nearest the footend 2 of the bedstead. Each of the said bent-over side members 6 of the footend flap of the knee-

rest section carries a runner wheel C3, each said wheel at the respective side of the knee-rest section being mounted in position a little above the connection of the loosely riveted cross-bar C5 to the corresponding bent-over side member 6 of the footend knee-rest flap. Each said runner wheel C3 is adapted to travel in an inclined wheel-rail or guide C4 which is suspended at its two ends from the respective side of the leg-rest section E near the footend of the latter, the direction of inclination of the said wheel-rails or guides C4 rising towards the headend 1 of the bedstead, as shown.

By this manner of forming and attaching the articulation formed by the wheel-rails or guides C4 of the knee-rest section to the footend of the leg-rest section E, and not to the frame-work T of the bedstead, the said knee-rest section retains its possibility of movement relatively to the leg-rest section E whether the said leg-rest section has previously been operated into the longitudinally moved and upwardly tilted or elevated position or not. Also, the said leg-rest section retains its independence for both upwardly tilting and longitudinal movement relatively to the bedstead frame-work when the screw B is operated.

When the screw C is operated, this causes the threaded sleeve C1 to travel forward on the said screw towards the headend of the bedstead and, upon doing so, causes the link-rods C2 also to move in the forward direction. These link-rods C2 thereby move the cross-bar C5 in the forward direction and the runner wheels C3 travel up the incline of the wheel-rails or guides C4, thereby varying the inclination of the two knee-rest flaps F relatively to one another and to the leg-rest section E owing to their relative articulations to one another at F1 and to the leg-rest section at the headend of the latter. The knee-rest flaps F may thereby be caused to assume various relative positions of inclination as shown in Figs. 4, 5, 6, 8, 9 and 11 and which will be more fully and particularly described hereinafter.

In addition to the constructional features above-described, the preferred form of bedstead in accordance with the invention as illustrated in the drawings also includes, for a purpose which will hereinafter be more fully described with reference to the manner of operation and use of the bedstead, a stop or abutment means O provided at the headend of the bedstead and which is formed, as shown, by two vertically spaced parallel cross-bars 7 and 8 interconnected by spaced vertical bars 9 so as to form an abutment or stop which tilts slightly from the bottom towards the footend of the bedstead. This stop serves the purpose of arresting the bodily longitudinal movement of the mattress towards the headend of the bedstead should the same take place, and after it has taken place over a determined distance, and also of arresting the circular movement of the back-rest section from normal should the latter subsequently tend to take place, all as will be more fully described hereinafter. Alternatively, vertical bars 10 in the headend 1 of the bedstead above the said stop O form a further abutment means adapted to perform the same function in dependence upon the degree to which the leg-rest section screw B has been operated, also as will be more fully described hereinafter.

However, also as will be more fully described hereinafter, the upwardly tilted but longitudinal moved position of the leg-rest section E may also take place towards the footend of the bed-

stead and the said preferred construction further includes, at either side of the footend of the leg-rest section E, hook holes K whereby upon such movement occurring the said footend of the mattress may be temporarily hooked by clamps K1 to the bedstead frame-work T against any further longitudinal movement relatively to the said frame-work, in order to enable the knee-flap-inclination-varying means thereafter to be operated, all as and for a reason which will also hereinafter be more fully described.

In the normal position of the bedstead as shown in Figs. 1 and 15, the three sections of the mattress are collapsed and substantially flat. The mattress as a whole is restedly supported at its head and footends on the cross-members of the bedstead frame-work T while it is supported on the said frame-work intermediate its ends by means of the projecting ends of the hinge-rod M about which the back-rest and leg-rest sections D and E respectively are articulated. This normal position is obtained by all the three operating screws A, B and C being operated to move the threaded sleeves A1, B1 and C1 toward the footend of the bedstead, the sleeve C1 and related link-rods C2 operating through the connection with the knee-rest section F to move the mattress as a whole to such position that the headend of the back-rest section D is spaced from the head-end 1 and the stop O, as shown in Figs. 1 and 15.

Other positions that may be obtained with the bedstead constructed in accordance with the invention are as follows:

(1) *Fowler (back-rest) position No. 1.*—This is shown in Fig. 10. With the three operating screws A, B and C all in their normal unoperated positions, and therefore with all the sections of the bedstead flat as shown in Figs. 1 and 15, the back-rest section screw A is alone operated. This moves the sleeves A1, the levers A2 and the hangers D1 towards the headend of the bedstead and elevates the said back-rest section D by pivotal movement about its hinge-rod M with the leg-rest section E, and the said back-rest section assumes the vertical position shown in Fig. 10.

(2) *Fowler (knee-rest) position No. 2.*—This is shown in Fig. 11. With the three operating screws A, B and C all in their normal unoperated positions, and therefore with all the sections of the bedstead flat as shown in Figs. 1 and 15, the knee-rest section screw C is alone operated. This moves the sleeve C1 and link-rods C2 towards the headend of the bedstead and varies the inclination of the two flaps F of the knee-rest section relatively to one another and to the leg-rest section E, the wheels C3 rolling on the rails C4 and the said knee-rest flaps assuming the positions shown in Fig. 11.

(3) *Fowler (back-rest and knee-rest combined) position No. 3.*—This is shown in Fig. 4 and is simply the combination of the Fowler positions Nos. 1 and 2 which is attained by first operating the screw A to raise the back-rest section D and then operating the screw C to adjust the knee-rest flaps F.

(4) *Reversed Trendelenburg position No. 2.*—This is shown in Fig. 5. With the three operating screws A, B and C all in their normal unoperated positions, and therefore with all the sections of the bedstead flat as shown in Figs. 1 and 15, the leg-rest section screw B is first operated. The mattress as a whole is prevented from moving towards the head-end of the bedstead by the knee-rest flaps F and the link-rods

C2 connecting the leg-rest section with the unoperated sleeve C1. As the screw B is operated and the adjacent ends of the back-rest section D and the leg-rest section E are raised during the travel of the wheels B3 along the rails B5, the levers B4 in their movement engage the cross bar D3 and swing the back-rest section D upwardly about the hinge-rod M until it assumes a position approximately parallel with the bedstead frame-work T as shown in Fig. 13. The back-rest section screw A is then operated to bring the said back-rest section D into a straight slanting line with the leg-rest section, the slant rising from the footend of the mattress towards the headend thereof as shown in Fig. 5. This is in fact the reversed Trendelenburg position No. 1 more particularly described with reference to Fig. 14. The footend of the mattress is then locked to the frame-work T by the hooking means K, K1 and the knee-rest section-operating screw C operated. The travel of the runner wheels C3 up the inclined wheel rails or guides C4 then operates the knee-rest flaps F in the manner previously described and they assume their relative inclinations and the inclinations to the leg-rest section E shown in Fig. 5.

(5) *Trendelenburg position.*—This is shown in Fig. 6. With the three operating screws A, B and C all in their normal unoperated positions, the knee-rest section-operating screw C is first fully operated. This forms the knee-rest triangle on the leg-rest section in the manner previously described. The leg-rest section screw B is then operated. The leg-rest section E, carrying with it the back-rest section D, moves longitudinally towards the headend 1 of the bedstead, the headend of the said leg-rest section being at the same time upwardly tilted or elevated and carrying with it the footend of the back-rest section. The said forward longitudinal movement takes place until the headend of the back-rest section engages against the abutment or stop O and the effect of such forward movement on the knee-rest flaps F is to reduce the inclination thereof to about half the maximum in spite of the fully operated condition of the screw C. The combination of the reduced knee-rest triangle thereby formed on the leg-rest section and of the larger triangle formed by the leg-rest section E and back-rest section D on the frame-work T of the bedstead, forms a large triangle with the knee-flaps-hinge-rod F1 at the apex and one of the knee-rest flaps F and the back-rest section D forming one side of the triangle and the other knee-rest flap F and the footend of the leg-rest section forming the other side, all as shown in Fig. 6.

Hyperextension position.—This is shown in Fig. 7. It may be obtained as described immediately above with the exception that after the operation above described has been carried out the screw C is turned half-way back in order to cause the reduced knee-rest triangle on the leg-rest section to disappear again as shown in Fig. 7. The single triangle left has then its apex at the hinge-rod M between the leg-rest section E and the back-rest section D.

(7) *Cardiac chair-like position No. 2.*—This is shown in Fig. 8. The operation of the leg-rest section screw B takes place exactly as described with reference to the reversed Trendelenburg position No. 2 shown in Fig. 5. The back-rest section screw A is then operated, to its fullest extent, namely until the operating link-rods A2 abut against the underside of the fully operated

cross-bar B6 and the back-rest section assumes the position shown in Fig. 8. This is in fact the convalescent position No. 1 which is hereinafter referred to in connection with Fig. 12. 5 The footend of the leg-rest section is then locked to the framework T by the hooking means K, K1 and the knee-rest section-operating screw C is operated only to the extent shown in Fig. 8 where that flap of the knee-rest section F which is nearest the headend of the bedstead extends substantially parallel to the frame-work T.

(8) *Convalescent position No. 3.*—This is shown in Fig. 9. The operation of the leg-rest section screw B takes place exactly as described with reference to the reversed Trendelenburg position No. 2 shown in Fig. 5. The back-rest section D is raised into the position substantially parallel to the bedstead frame-work T by engagement of the levers B4 with the cross bar D3, but there is no specific operation of the back-rest screw A itself. The footend of the leg-rest section is then locked to the frame-work T by the hooking means K, K1 and the knee-rest section operating screw C is operated to bring the knee-rest flaps F into the position shown in Fig. 9.

(9) *Convalescent position No. 1.*—This is shown in Fig. 12. The operation of the leg-rest section screw B takes place exactly as described with reference to the reversed Trendelenburg position No. 2 shown in Fig. 5. The back-rest section screw A is then operated, however, to its fullest extent, namely until the operating link-rods A2 abut against the underside of the fully operated cross-bar B6 and the back-rest section 30 assumes the position shown in Fig. 12, the sections D and E being held in position adjacent the footend of the bedstead by the unoperated condition of the knee-rest section screw C and without the employment of the hooking means K, K1.

(10) *Convalescent position No. 2.*—This is shown in Fig. 13. As previously described, this position of the various sections of the mattress is obtained simply by operating the leg-rest section screw B with the two other operating screws A and C in their normal unoperated positions. In addition to the leg-rest section E being held in position adjacent the footend 2 of the bedstead, with the headend thereof tilted or elevated into the raised position, the back-rest section D with its attendant operating means, due to the engagement of the levers B4 with the cross bar D3, is also raised bodily from the bedstead frame-work T while maintaining its normal parallel position thereto. The positions described are maintained by the unoperated condition of the knee-rest section screw C which exerts the previously described restraining and maintaining force on the footend of the leg-rest section E.

(11) *Reversed Trendelenburg position No. 1.*—This is shown in Fig. 14. The operation is exactly as described with reference to the convalescent position No. 2 of Fig. 13 except that the screw A is operated to an extent such that the said back-rest section forms a straight line with the upwardly slanting leg-rest section shown in Fig. 14.

I claim:

1. In a hospital-type bedstead installation, the combination of a mattress supporting frame, leg-rest and back-rest mattress sections arranged end to end and supported upon said frame, means pivotally connecting the adjacent ends of the sections, operating means for applying a force to the pivoted end of the leg-rest section and tend-

ing to move the same in an inclined longitudinal direction, means at the footend of the leg-rest section to restrain the latter from moving longitudinally whereby the force applied by the operating means is rendered effective to variably elevate the pivoted end of the leg-rest section, and operating means for moving the back-rest section about said pivot means.

2. A bedstead as claimed in claim 1 wherein the second mentioned operating means is operable to apply a turning force to said back-rest section acting in a direction toward that end of said back-rest section opposite the pivoted end.

3. A bedstead as claimed in claim 1 wherein each of said operating means includes an actuating member and link means free from direct pivotal connection to said frame and connected at one end to the actuating member and at the other end to the related mattress section.

4. In a hospital-type bedstead installation, the combination of a mattress supporting frame, leg-rest and back-rest mattress sections arranged end to end and supported upon said frame, means pivotally connecting the adjacent ends of the sections, operating means for applying a force to the pivoted end of the leg-rest section and tending to move the same in an inclined longitudinal direction, knee-rest flaps pivotally connected to one another and to said leg-rest section, operating means for varying the inclination of the flaps relatively to one another and to said leg-rest section, said flaps and the related operating means being effective in the normal unoperated condition thereof to restrain longitudinal movement of the leg-rest section whereby the force applied by the first mentioned operating means is rendered effective to variably elevate the pivoted end of the leg-rest section.

5. In a hospital-type bedstead installation, the combination of a mattress supporting frame, leg-rest and back-rest mattress sections arranged end to end above said frame, means pivotally connecting the adjacent ends of the sections, operating means for applying a force tending to move the pivoted end of the leg-rest section in an inclined longitudinal direction, knee-rest flaps pivotally connected to one another and to said leg-rest section, operating means for varying the inclination of the flaps relatively to one another and to said leg-rest section, said flaps and the related operating means being effective in the normal unoperated condition thereof to restrain longitudinal movement of the leg-rest section whereby the force applied by the first mentioned operating means is rendered effective to variably elevate the pivoted end of the leg-rest section, the second mentioned operating means being operable to move the back and leg-rest sections as whole toward the foot end of the frame during operation of the first mentioned operating means, and means to lock the leg-rest section to the frame before operation of the operating means for the knee-rest flaps.

6. In a hospital-type bedstead installation, the combination of a mattress supporting frame, mattress sections supported upon the frame and including a leg-rest section and a knee-rest section disposed above and supported on the leg-rest section, said knee-rest section including flaps pivotally connected together and to said leg-rest section, operating means for applying a force to the pivoted end of the leg-rest section tending to move the same in an inclined longitudinal direction, operating means for varying the inclination of the flaps relatively to one another

and to said leg-rest section, the second mentioned operating means including members effective in the unoperated position thereof to restrain the leg-rest section from longitudinal movement whereby the force applied by the first mentioned operating means is rendered effective to variably elevate the pivoted end of the leg-rest section.

7. In a hospital-type bedstead installation, the combination of a mattress supporting bed frame, mattress sections supported upon said frame and including a leg-rest section and a knee-rest section disposed above and supported on the leg-rest section, said knee-rest section including flaps pivotally connected together and to said leg-rest section, operating means for moving the end of the leg-rest section nearest the headend of the bed frame to cause said leg-rest section to bodily assume positions inclined upwardly toward the headend thereof, operating means for varying the inclination of the flaps relatively to one another and to said leg-rest section.

8. A bedstead as claimed in claim 7 wherein each of said operating means includes an operating screw mounted on said frame.

9. In a hospital-type bedstead installation, the combination of a mattress supporting bed frame, leg-rest and back-rest mattress sections arranged end to end and supported upon said frame, means pivotally connecting the adjacent ends of the sections, operating means for applying a force to the pivoted end of the leg-rest section tending to move the same in an inclined longitudinal direction, and operating means for moving the back-rest section about said pivot means, the first mentioned operating means being effective, when the second mentioned operating means is in unoperated condition, to move both sections longitudinally toward the head of the bed frame and to simultaneously move their pivoted ends upwardly.

10. A bedstead as claimed in claim 9 wherein abutment means is provided for engagement by the headend of the back-rest section to limit the movement of the sections toward the head of the bed frame.

11. A bedstead as claimed in claim 9 provided with knee-rest flaps pivoted together and to the leg-rest section, operating means for moving the flaps at an inclination to each other and to the leg-rest section, the third mentioned operating means and flaps being effective, in the unoperated condition thereof, to restrain the leg-rest section from longitudinal movement, and means to lock the leg-rest section to the bed frame to condition the flap operating means for operation.

12. In a hospital-type bedstead installation, the combination of a mattress supporting bed frame, leg-rest and back-rest mattress sections arranged end to end and supported for longitudinal movement upon said frame, means pivotally connecting the adjacent ends of the sections, links pivoted to the pivoted end of the leg-rest section, runner wheels at the ends of the links, inclined guides for said wheels supported by said frame, an operating screw carried by the frame, a threaded sleeve fitted on said screw, links connecting said sleeve with the wheeled ends of the first links, and abutment means at the headend of the frame for limiting the longitudinal movement of the sections in the direction of the headend of the bed frame.

13. In a hospital-type bedstead installation, the combination of a mattress supporting frame,

a leg-rest section supported upon the frame, a knee-rest section pivotally connected at one end to the leg-rest section and including flaps pivotally connected together, pivoted links depending from one end of the leg-rest sections, runner wheels at the ends of the links, inclined guides for said wheels supported on said frame, an operating screw mounted on the frame, a sleeve threaded on said screw, links connecting the sleeve with the wheeled ends of the first links, runner wheels on the flaps at the opposite end of the knee-rest section, inclined guides for the second wheels wholly supported by the leg-rest section, a second operating screw mounted on the frame, a sleeve threaded on the second screw, and link means connecting the second sleeve with the last mentioned end of the knee-rest section whereby during manipulation of the second screw the second wheels are caused to roll along the related guides to vary the inclination of the flaps relatively to one another and to said leg-rest section.

14. A bedstead as claimed in claim 13 provided with a back-rest section supported upon the frame, means pivotally connecting the adjacent ends of the back and leg-rest sections, the first links being connected with the leg-rest section

adjacent said pivot means, and means for moving the back-rest section about said pivot means.

15. A bedstead as claimed in claim 13 provided with means for releasably locking the leg-rest section against movement longitudinally of the frame.

HASSANALLY KHIMJI KHAKIANI.
